Company, Inc., Bridgeport, Conn., a corpora-
tion of Delaware

Application February 29, 1944, Serial No. 524,396

7 Claims. (Cl. 226—2)

1

The present invention relates, in general, to apparatus for assembling articles, and, in particular, to an improved agitating device for supporting article holding plates or blocks which are adapted to receive articles in separate recesses and orient the articles in a predetermined position.

In the manufacture of articles such as cartridges, the component parts of the cartridges, and, in particular, the bullets are made separately in large lots and subsequently assembled in the loaded cases to complete the cartridges. Various devices have been used to enable handling of the bullets in quantity production lots with the speed and dexterity requisite of present production schedules. Characteristic of these devices are apertured plates hereinafter referred to as holders or holding blocks for supporting the bullets in orderly arrangement so that like portions of all the bullets extend in the same direction. Certain types of bullet holding blocks known in the art as "transfer plates" embody an auxiliary plate which is slidably mounted in the holder and adapted to temporarily support the bullets in the apertures of the holding block and to be moved so as to release the bullets whereby they may drop down through the apertures of the block. These transfer plates are particularly suited for assembling bullets into the mouths of loaded cartridge cases. Other types of holding blocks are adapted to temporarily support the bullets for transfer into other apertured plates, the transfer being made by inverting the superposed assembled plates. For example, when dipping bullets into a colored lacquer bath, an apertured plate is chosen which is adapted to support the bullets so that a portion of the nose of each bullet will project from the bottom of the apertured plate when the latter is inverted permitting a predetermined length of the nose of each bullet to be coated with lacquer.

Heretofore, bullets have been fed into the apertures of bullet holding transfer blocks by supporting the blocks on a shaker frame and ladling the bullets onto the top surface of the apertured block. This method has however occasioned a serious loss of time due to the necessity for alternately starting and stopping the shaker each time the holder block was filled and removed and for reorienting a relatively large percentage of the bullets.

The present invention provides an improved shaker for supporting a plurality of bullet holding blocks and is characterized by improved performance which more than doubles the rate of production of earlier types of shakers.

2

In the drawings:

Fig. 1 is a diagrammatic showing of the improved bullet distributor of this invention including a hopper for feeding bullets to the distributor and a conveyor belt to recirculate bullets from the distributing device to the hopper.

Fig. 2 is a perspective view of the bullet distributor frame including an apron onto which the bullets are delivered from a hopper and guides for supporting the bullet holders.

Fig. 3 is a side elevation partly in section of the bullet distributor showing the frame supporting means and the bullet receiving receptacle located beneath the distributor.

Fig. 4 is a side elevation in section of one of the bullet holding blocks.

Fig. 5 is a fragmentary plan view of one of the bullet holding blocks.

Referring to the drawings, the bullet distributor or shaker embodies a substantially rectangular frame indicated generally at 11 in Fig. 2 comprising side members 12 and end members 13. Both the side and end members are formed of a suitable material and are of a configuration to combine strength with lightness. In the embodiment shown, the members comprise angle iron stock but other suitable material may be used. A brace 14 is fastened between the side members 12 at substantially the center of the frame and is provided with a plurality of apertures 15 in the top surface thereof for the purpose hereinafter described.

Welded or otherwise secured on the bottom of each corner of the frame is a substantially rectangular hard metal plate 16 adapted to constitute a bearing surface for floatingly supporting the frame on suitable rollers 17 which are rotatably mounted on fixed trunnions 18 extending laterally and at longitudinally spaced points from the inside wall of a pair of spaced parallel rails 19. The latter are fixedly secured at their opposite ends between the end walls 20 and 22 respectively of a bin or receptacle indicated generally at 23, see Fig. 3 and hereinafter described.

In accordance with this construction, the distributor frame 11 is movably supported by the fixed rails 19 in the upper open end of the bin 23. The frame is given a reciprocating motion of relatively short stroke by providing a yoke-shaped connecting rod 24 which is connected at its bifurcated ends by suitable bearing blocks 25 to a transverse rod 26 of the frame 11. The opposite end of the connecting rod is pivotally connected to an eccentric pin 27 of a disk 28 which is keyed to a drive shaft 29 conveniently

supported in bearings on the front wall 20 of the bin 23. When the shaft 29 is rotated, the eccentric pin and connecting rod transmit a relatively violent shaking or agitating motion to the frame, the latter riding freely on the rollers 17.

Referring to Figs. 2 and 3, an angle bar 30 is shown mounted on the right hand end of the frame 11 and is fixedly secured to the end piece 13 by suitable fastening means such as welded joints. The vertical leg of the bar 30 is provided with a plurality of apertures 32 and is adapted to form a flange for supporting an article dispersing member or apron 33. The latter is a substantially rectangular plate provided with transversely spaced V-shaped notches 34 in its forward edge and a flange 35 depending at substantially right angles at its rear end. The flange 35 has a plurality of longitudinally disposed slots 36 corresponding in number to the apertures 32 of the angle bar 30 and adapted to receive bolts 37 whereby the apron member may be adjustably fastened to the bar 30. In accordance with this construction, the apron member may be adjusted vertically with respect to the frame 11. The apron is made sufficiently rigid by providing depending flanges 38 along the sides thereof while upwardly and outwardly extending flanges 39 are provided to prevent cartridges from falling off the sides of the apron.

Secured on the forward end of the movable frame 11 is an angle bar 40, the vertical leg of which is provided with longitudinal slots 42 to receive adjusting bolts 43. The latter are secured in corresponding apertures 44 to the end piece 13 and serve to fasten the angle bar 40 thereto and to enable adjustment of the bar 40 vertically with respect to the frame.

Supported on the brace 14 is an angle bar member 45, the lower edge of its upright leg being in engagement with the top of the brace 14. The bar 45 is held adjustably in this position by means of a plurality of bolts 46 which extend through suitable holes 47 in the laterally disposed portion 45' of the bar and are received in the corresponding apertures 48 of the brace. Suitable nuts 49 on the bolts 46 are adapted to fasten the bolts securely to the brace 14 and to the bar 45.

Mounted on the angle members 40 and 45 are a plurality of guide members 50 and 52 which are adapted to support the cartridge holding blocks or plates in the frame 11. Each guide member 50 comprises a longitudinal rib portion 53 preferably provided with a bevelled upper edge 54 and tapered forward and rearward ends 55 and 56 respectively. The taper at each end of the rib, and, in particular, the rear end 56 is adapted to correspond to the V-shaped notches 34 of the apron 33 so as to make a nice fit therein for the purpose hereinafter described. Extending laterally from each side of a rib 53 and at substantially right angles thereto is a flange 57 which is welded or otherwise formed on the lower edge of the rib and extends from the front end thereof rearwardly. The length of the flange is substantially four-fifths of the length of the rib and terminates in a downwardly curved tail portion 58. The forward end of the flange is turned up at substantially right angles to form a projection or lip 59, the upper edge of which is curled over to provide a smooth rounded surface. In the present embodiment, three of these guide members 50 are mounted in spaced parallel relationship on the upper plane surfaces of the angle members 40 and 45, each guide being

permanently fastened to the angle members by welded joints or other suitable fastening means.

The guide members 52, of which there are two, are similar to the guides 50 but are adapted to be welded to the outer ends of the angle members parallel to the inner guides 50. To this end, each outer guide member 52 has a single inwardly extending flange 57' which is substantially similar to the flanges 57. The upper longitudinal edge of each outer guide member 52 comprises an upwardly and outwardly flared flange 54'.

The auxiliary frame comprising the two angle bar members 40 and 45 and the guide members 50 and 52 welded thereto may be adjusted with respect to the main frame 11 by moving the angle bars vertically so as to vary the slope or inclination of the auxiliary frame, and hence the flanged portions 57 and 57' of the guide members. As pointed out above, the rear bevelled ends of the guide members 50 are adapted to be engaged in the respective V-shaped notches 34 of the apron 33 which hold the rear end portions of the guides 50 in proper spaced parallel relationship while permitting adjustment of the guide members relative to the apron. In accordance with this construction, the inclination of the holding blocks which are adapted to be supported on the flanges 57 and 57' of the auxiliary frame is adjustable to correspond to the inclination of the apron 33 whereby the upper surfaces of the blocks will lie substantially in the plane of the apron.

The cartridge holding blocks 60, one of which is shown in Figs. 4 and 5, comprises a flat substantially rectangular wooden base portion 62, a fiber board top portion 63 and a metal bottom plate 64. As shown, a plurality of counterbores are formed in the fiber board portion in axial alignment with apertures in the wooden portion of the block. In the present embodiment, each holder block contains one hundred and forty-seven counterbored apertures, but it will be understood that the number and configuration of the apertures may be altered to accommodate articles of various sizes and weights and that the holder block itself may comprise other suitable materials. The metal bottom plate 64 may be turned up over the ends of the wooden portion of the block to provide a long wearing surface for the ends as well as for the bottom of the holder. Suitable projections or tongues 66 and 67 are formed integrally at each end respectively of the fiber bore portion of the holder block to facilitate handling thereof and to provide locking means therefor as described below.

As shown in Figs. 1 and 3, each holder is adapted to be slipped between a pair of guide members 50 and to be supported therebetween on the flanges thereof, the front edge or shoulder 64' of a holder block being seated behind the lip portions 59 of the corresponding flanges. The tongue 67 at the rear end of the holder block is adapted to extend beneath the forward notched edge of the apron 33 and to abut a projection or rib 68 which is fastened to the apron and which extends transversely across the apron parallel to its forward edge.

The rib 68 constitutes a stop member which properly locates the holder block in the guide members 50 in juxtaposition to the apron. Moreover, the rib or stop 68 and the lips 59 of the holder supporting flanges 57 are spaced apart a predetermined distance such that a holder block will be securely locked therebetween while bullets are being distributed therein from the apron by the shaking motion of the frame. When a holder

has been filled, the operator may seize its forward tongue 66 and lift the holder upwardly over the lips 59 and readily withdraw it by pulling it forwardly in the direction of motion of the shaking frame 11 without interrupting the distribution of bullets into the other holding blocks in the frame.

As shown in Figs. 1 and 3, the cartridges are delivered onto the dispersing apron 33 from the discharge spout 69 of a hopper 70 which is conveniently located above and adjacent the rear end of the apron. Due to the shaking motion of the frame, the bullets being discharged onto the apron will be wildly scattered over the surface thereof and will slide and roll down therefrom across the counterbored surfaces of the holder blocks 60. The construction and dimensions of the counterbores are such that each bullet will automatically enter into an aperture heel end first in a well known manner.

As pointed out above, the holder block supporting frame 11 is mounted above the receptacle 23 to the end that when a filled block 60 is removed from the frame during continuous operation of the shaker, bullets rolling off of the dispersing apron 33 will be collected in the bottom 72 of the receptacle. The latter is inclined, as shown, and provided with a discharge port 73 whereby the bullets may be removed from the bottom of the receptacle.

In the present embodiment, the discharge port 73 of the receptacle is adapted to discharge the bullets onto the lower end of a suitable conveyor belt 14 which is arranged to return the bullets into the top of the hopper 70. It will be clear, therefore, that for any one filling or charging of the hopper, the bullet shaker may be run continuously until all bullets have been oriented and distributed into the holder blocks and that the operator's only duty is to withdraw and empty each holder block as it is filled and to return the empty blocks back into the shaker. As each block is replaced in the shaker, it is securely locked therein between the projections 59 and stop 68 without interrupting the continuous operation of the machine. Moreover, the same shaker is readily adapted for orienting and distributing articles of different dimensions and weights by varying the inclination of the apron and apertured plates as described.

As is evident from the drawings, the blocks are supported on the flanges of the guide members with the longitudinal axis of the blocks parallel to the direction of motion of the shaker frame, and, in accordance with this construction, the blocks are withdrawn from and inserted into the frame by moving the blocks in the direction of reciprocation of the frame which greatly facilitates the handling of the blocks.

What is claimed is:

1. Apparatus for automatically distributing articles comprising a movable frame; article dispersing means fixed to said frame; an article holder; means on said frame constructed and arranged to support the article holder adjacent said dispersing means and means for moving said frame to cause displacement of said articles from said dispersing means into said holder, said article holder being selectively removable from said supporting means for ejecting articles from said holder.

2. Apparatus for automatically orienting and distributing articles into an apertured block comprising a movable frame; an article dispersing apron on said frame adapted to support articles; means for adjusting the inclination of said apron

with respect to said frame; a pair of spaced parallel flanges carried by said frame and constructed and arranged to support the apertured block in the plane of said apron; and projections on said flanges to removably retain said apertured block in juxtaposition to said apron.

3. In a machine for distributing articles into a holder, the combination with a movable frame adapted to removably support a holder and means for agitating said frame; of means for continuously delivering articles to said holder comprising a frame supporting receptacle having an opening in the top thereof beneath said holder, and a discharge port in the bottom thereof; a hopper adjacent said holder constructed and arranged to feed articles to said holder above the top opening of said receptacle; and conveyor means adjacent said discharge port to return articles to said hopper which fall from said hopper into said receptacle when a filled holder is removed from the frame.

4. In a machine for distributing articles into a holder, the combination with a movable frame having an article dispersing member, means carried by said frame to removably support said holder adjacent said dispersing member, and means for agitating said frame whereby articles on said dispersing member will be displaced into said holder; of means for constantly feeding articles onto said dispersing member comprising a frame supporting receptacle having an opening in the top thereof immediately beneath said holder and a discharge port in the bottom thereof; a hopper adjacent said holder constructed and arranged to discharge articles onto said dispersing member; and conveyor means adjacent said discharge port to receive articles which fall from said dispersing member into said receptacle when a filled holder is removed from the frame and to return such articles to said hopper.

5. Apparatus for automatically distributing articles into a plurality of apertured plates comprising a movable frame; an apron on said frame adapted to support articles; means for agitating said frame whereby articles on said apron are displaced therefrom into the apertures of said plate; and means for supporting said plates to enable removal of a filled plate from said supporting means without interruption in the movement of said frame, said supporting means comprising flanged members carried by said frame and projections on each flanged member to engage a portion of a plate to releasably retain said plate in juxtaposition to said apron.

6. Apparatus for automatically distributing articles into a holder comprising a stationary frame; a movable frame mounted on said stationary frame; an article dispersing apron fixed to said movable frame; an article holder; means on said movable frame constructed and arranged to removably retain said holder on said movable frame in juxtaposition to said apron; and means for agitating said movable frame and said apron to displace articles from said apron into said holder, said holder retaining means being arranged to permit removal of said holder from said movable frame while said movable frame is being continuously agitated by said agitating means.

7. Apparatus for automatically distributing articles into a holder comprising a stationary frame; a movable frame mounted on said stationary frame; an article dispersing apron fixed to said movable frame; an article holder; means

on said movable frame and said apron constructed and arranged to cooperatively engage opposite ends of said holder so as to removably retain said holder on said movable frame in juxtaposition to said apron; and means for agitating said movable frame and said apron to displace articles from said apron into said holder,

said holder retaining means being arranged to permit removal of said holder from said movable frame while said movable frame is being continuously agitated by said agitating means.
